UNITED STATES PATENT OFFICE

2,447,078

EAR MUFF

Robert E. Maxant, Riverside, Ill., assignor to
 Maxant Button & Supply Co., Chicago, Ill., a
 corporation of Illinois

Application February 1, 1947, Serial No. 725,926

4 Claims. (Cl. 2-209)

1

This invention relates to ear muffs and more particularly to improvements in the type of ear muffs shown in L. E. McDonough Patent No. 2,216,954, issued October 8, 1940.

In said McDonough patent an outer covering and an inner liner are clamped between a flanged annular frame and a ring to provide an ear muff wherein the liner is worn adjacent to the ear and a band fastener extends through a slit in the liner and is carried by the ring.

The principal object of this invention is to provide an improved ear muff wherein the liner is entirely omitted, wherein the covering is worn adjacent the ear, wherein an exposed solid frame is substituted for the ring to add strength to the ear muff and to provide for a decorative or two-tone appearance, and wherein the band fastener extends through a slit in the covering.

Other objects and advantages will become apparent to those skilled in the art upon reference to the accompanying specification, claims, and drawing, in which—

Fig. 1 is a perspective view of a pair of ear muffs;

Fig. 2 is an exploded perspective view of an ear muff made in accordance with one form of this invention;

Fig. 3 is a sectional view through the ear muff of Fig. 2, taken substantially along the line 3—3 of Fig. 1;

Fig. 4 is a sectional view similar to Fig. 3 but showing another form of the invention; and

Fig. 5 is an exploded perspective view of the parts of the ear muff illustrated in Fig. 4.

Referring to the drawing, Fig. 1 illustrates a pair of ear muffs 10 each provided with a band fastener 11 pivotally connected to a flexible band 12 by pivots 13. The band 12 is composed of two adjacent flexible strips of metal upon one end of each of which is secured an ear muff 10 and on the other end a ring 14 which provides a loop through which the other flexible strip may slide so that the flexible band 12 may be extended in length, if desired, to accommodate heads of different sizes.

The ear muff 10, as illustrated in Figs. 2 and 3 includes a flanged annular frame 16 having a supporting portion 17 and a flange portion 18. Preferably, the flange portion 18 is provided with a series of notches 19 to permit the edge of the flange adjacent the notches 19 to be turned inwardly. The flanged annular frame 16 is provided with a bracket 20 having a pair of slots 21. The bracket 20 is folded back upon itself at 22 with the slots 21 in alignment and the folded

2

portion 22 acts as a pivot for the band fastener 11. One end of the band fastener 11 is provided with a loop 23 extending through the slots 21 so that the loop 23 is pivotally mounted on the portion 22 of the bracket. The other end of the band fastener 11 is provided with a hole 24 for receiving the pivot pin 13 for securing the same to the flexible band 12.

A covering 26, preferably made of a heavy pile fabric, or fur or the like, is provided with a slit 27 for accommodating the band fastener 11. The covering 26 is applied to the flanged annular frame 16 with the edges of the covering completely overlapping the flange 18 of the frame, as indicated at 28 in Fig. 3.

The solid frame 30 is concavo-convex in configuration and it is provided with a marginal rim 31 adapted to be received within the flange 18 of the flanged annular frame 16. When it is so received, the overlapping edge 28 of the covering 26 is interposed between the rim 31 and the flanged annular frame 16, as indicated in Fig. 3. The edge of the flange 18 is then bent over, this being permitted by the notches 19, to clamp the covering between the solid frame 30 and the annular frame 16.

When the parts are being assembled, as described above, the band fastener 11 is inserted through the slit 27 in the covering 26. The ear muff thus formed has the covering 26 adjacent the ear of the wearer and the solid frame 30 exteriorly. The solid frame 30, if desired, may be colored differently than the coloring of the covering 26 to provide a pleasing two-tone, decorative effect, and if desired suitable ornamentation may be applied to the solid frame 30, as indicated at 32 in Fig. 1.

The form of the invention illustrated in Figs. 4 and 5 is the same as that illustrated in Figs. 2 and 3, with the exception that the band fastener 11 is pivotally carried by the solid frame 30 rather than by the flanged annular frame 16. In this connection a bracket 35 is suitably secured to the interior of the solid frame 30, as by spot welding, and the bracket 35 is provided with a slot 36 for receiving the loop 23 of the band fastener 11 whereby the band fastener 11 is pivotally mounted at 37. Here as in the previous form of the invention, the band fastener 11 extends through a slit 27 in the covering 26.

While for purposes of illustration two forms of this invention have been disclosed, other forms thereof may become apparent to those skilled in the art upon reference to this disclosure, and, therefore, this invention is to be

limited only by the scope of the appended claims and prior art.

I claim as my invention:

1. An ear muff comprising a flanged annular frame, a covering for the frame and completely overlapping the flange thereof and adapted to be worn adjacent the ear, a solid frame received in the annular frame with the covering clamped between the solid frame and the flange and adapted to be exposed when worn, and a band fastener extending through a slit in the covering and carried by one of said frames.

2. An ear muff comprising a flanged annular frame, a covering for the frame and completely overlapping the flange thereof and adapted to be worn adjacent the ear, a solid frame received in the annular frame with the covering clamped between the solid frame and the flange and adapted to be exposed when worn, a pivot formed on the annular frame, and a band fastener extending through a slit in the covering and carried by the pivot.

3. An ear muff comprising a flanged annular frame, a covering for the frame and completely overlapping the flange thereof and adapted to be worn adjacent the ear, a solid frame re-

ceived in the annular frame with the covering clamped between the solid frame and the flange and adapted to be exposed when worn, a pivot carried by the solid frame, and a band fastener extending through a slit in the covering and carried by the pivot.

4. An ear muff comprising a flanged annular frame, a covering for the frame and completely overlapping the flange thereof and adapted to be worn adjacent the ear, a concavo-convex solid frame received in the annular frame with the concave side facing the covering and with the covering clamped between the solid frame and the flange and adapted to be exposed when worn, and a band fastener extending through a slit in the covering and carried by one of said frames.

ROBERT E. MAXANT.
